UNITED STATES PATENT OFFICE

JOE BROWN, OF GRANITE CITY, ILLINOIS

DESIGN FOR A CABINET-RANGE

Application filed November 14, 1931. Serial No. 41,732. Term of patent 14 years.

To all whom it may concern:

Be it known that I, JOE BROWN, a citizen of the United States, residing at Granite City, county of Madison, State of Illinois, have invented a certain new, original, and ornamental Design for a Cabinet-Range, of which the following is a specification, reference being made to the accompanying drawing, forming a part thereof, in which the figure is a perspective view of a cabinet-range embodying my new design.

I claim—

The ornamental design for a cabinet-range substantially as shown.

JOE BROWN.
